UNITED STATES PATENT OFFICE.

ELMER E. PATTEN, OF ST. LOUIS, MISSOURI, ASSIGNOR TO ST. LOUIS CASH REGISTER COMPANY, OF ST. LOUIS, MISSOURI, A CORPORATION OF MISSOURI.

REGISTER MECHANISM.

1,125,389.

Specification of Letters Patent.

Patented Jan. 19, 1915.

Application filed May 5, 1913. Serial No. 765,672.

To all whom it may concern:

Be it known that I, ELMER E. PATTEN, a citizen of the United States, residing at the city of St. Louis, State of Missouri, have invented a certain new and useful Improvement in Register Mechanism, of which the following is a full, clear, and exact description, such as will enable others skilled in the art to which it appertains to make and use the same, reference being had to the accompanying drawings, forming part of this specification, in which—

Figure 1 is a front elevational view of the register mechanism comprising my invention. Fig. 2 is a sectional view taken approximately on the line 2—2 of Fig. 1. Fig. 3 is an end elevational view partly in section looking at the right of Fig. 1. Fig. 4 is a detail of the hundreds carrying mechanism. Fig. 5 illustrates the re-setting hand wheel and its coöperating pawl. Fig. 6 is a detail showing the ratchet connection of indicator wheels and hand shaft.

My invention relates to registering mechanism, and particularly to a simple form of register adapted for use in the form of cash register illustrated, described and claimed in my copending applications, Nos. 647,821, filed September 2, 1911, and 704,995, filed June 21, 1912. As illustrated in the accompanying drawings, it will be seen that this register is adapted to accumulate numbers by simple addition, and to carry from order to order.

The principal object of my invention is to provide a register with a form of resetting mechanism which is designed to rock all parts having engagement with the accumulating wheels, out of engagement therewith at the beginning of the re-setting operation, to hold said parts while out of engagement with the accumulating wheels, in proper position for reengagement therewith, and to insure all of the accumulating wheels being returned to zero position before their actuating mechanism is reengaged with them, and to prevent any overthrow or advance of any of the accumulating mechanism when the operating parts are reengaged with it.

Most features of the construction illustrated in the drawings and hereinafter described have been disclosed in one or the other of my copending applications referred to above and this application constitutes a composite continuation of them.

By reference to the applications above mentioned, and to the drawings which are part of this application, it will be seen that the registering mechanism is mounted upon a pair of side frames 1 which are connected by the setting shaft 2 and pawl shaft 4, the said frame and its carried parts being pivotally mounted in the cash register upon pivot shaft 5. Sleeved upon setting shaft 2 is 60 5¢ register plate 6 with which is conjoined the 5¢ indicator 7; the 10¢ accumulating wheel 8, with which are conjoined 10¢ carrying cog 9, 10¢ indicating disk 10, and dollars tripping pawl 11; dollars carrying 65 cog 12 with which are conjoined dollars indicating disk 14 and tens of dollars tripping pawl 15. The mechanism for each column of higher order consists in an accumulating wheel 16, indicator disk 17, and carrying pawl 18 for each order. As illustrated in 70 Fig. 6, with the exception of 5¢ plate and indicator, each of the groups of combined parts just described has ratchet engagement with setting shaft 2, by virtue of which the parts may move progressively on the shaft, 75 but not rearwardly thereon, so that when setting shaft 2 is rotated progressively it carries with it all of the parts sleeved thereon.

The means for actuating the accumulating 80 parts so as to insert numbers into the register consist of the T-shaped lever 19 and the proper number of rack segments 20, each of which is controlled by a separate differentially operable plate 21 as set out in the applications before mentioned.

As described in the application last above mentioned, the carrying means for carrying from units to tens order consists of carrying pawl 22 which is oscillated longitudinally 95 at each operation of the machine by link 24, which is actuated by pinions 25, which in turn derives its movement from segment 26. Normally, carrying pawl 22 is held out of engagement with tens cog 9 by tripping pawl 27 which engages an ear 28 on carrying pawl 22. Tripping pawl 27 is mounted on shaft 4 and carries at its rearward extremity a lug 27a. As described in my application No. 704,995, a lug 19a carried by 100 T-shaped lever 19 is adapted to coöperate with 5¢ plate 6 above and below an apex 6a on said plate, so as to rock said plate alternately in opposite directions about shaft 2. As shown in Fig. 2, plate 6 stands at zero 110

position, and upon the operation of 5¢ plate 21 to insert 5 into the register, lug 19^a will travel below apex 6^a and swing plate 6 so that 5 will appear through the sight opening. At the next operation, lug 19^a will travel above the apex 6^a and at the same time arm 19^b on lever 19 will engage the lug 27^a to trip tripping pawl 27 and allow carrying pawl 22 to be disengaged from the shoulder on the forward end of tripping pawl 27. Upon the completion of the operation, when carrying pawl 22 is oscillated, it will engage cog wheel 9 so as to rotate it one space, together with the conjoined tens wheel 8, indicator 10 and tripping pawl 11, thereby inserting a digit into the tens register. There is a similar tripping pawl 29 for controlling the operation of the second carrying pawl 30 which carries from tens to hundreds. This tripping pawl 29, however, is tripped by tripping lug 11, which is rotated with tens wheel 8.

The mechanism for carrying from hundreds to thousands and between the succeeding higher orders consists of the well-known Geneva carrying mechanism which is operated by the carrying tooth 15. This Geneva carrying mechanism is carried in a frame 31 which is mounted upon shaft 4 and is held in engagement with the accumulating wheels by means of a spring 32.

The re-setting mechanism comprises means whereby all of the carrying mechanism may be rocked out of engagement with the accumulating mechanism while the accumulating mechanism is being returned to zero position by the progressive rotation of shaft 2. Mounted on shaft 34 is a rocking frame 35 which engages carrying pawls 22 and 30. Frame 31 which carries the Geneva carrying mechanism has a projecting arm 31^a which is also engaged by rocking frame 35. When swung outwardly or forwardly, rocking frame 35 swings carrying pawls 22 and 30 completely away from the accumulating mechanism. By virtue of this engagement, the forward movement of rocking frame 35, by virtue of its engagement with arm 31^a, also operates to swing the frame 31 so as to move the Geneva carrying mechanism out of engagement with the accumulating mechanism. A means for returning 5¢ plate 6 to zero position is also provided and consists of lever 36 which engages rocking frame 35 so as to be swung thereby, and which has a lug 36^a which, when lever 36 is swung by rocking frame 35, engages a lug 7^a on the 5¢ indicator plate, and pushes it rearwardly so as to return the 5¢ plate and indicator to zero position. Upon frame 31 are carried spring fingers 37 which, when frame 31 is swung rearwardly during the re-setting operation, engage accumulating wheels 16 to prevent overthrow and to insure their being cor-

rectly engaged by the teeth on the Geneva carrying wheels. A means is also provided for holding the Geneva carrying wheels in proper position while disengaged from the accumulating mechanism, which means consists of a spring plate 40 which engages the stop plate 41 of the Geneva movement and holds it in proper adjustment relative to the accumulating wheels.

The means for rocking rocking frame 35 and all of the parts controlled thereby, consists of snail cam 42 carried on shaft 2, cam lever 44, and stop lever 45. Stop lever 45 is connected with rocking frame 35 by means of an ear 45^a. When standing in zero position, the cut away portion of snail cam 42 is in position to receive the end of cam lever 44, but when shaft 2 is rotated to perform the re-setting operation, the end of cam lever 44 is swung out of the mutilated portion of the cam and is rocked upwardly against ear 45^a so that in its continued upward movement, cam lever 44 carries with it stop lever 45, and thus rocks rocking frame 35 and the parts coöperating therewith. When stop lever 45 is held in elevated position by cam lever 44, its upper end, which is provided with a notch 46, lies in the path of a pin 47 carried upon snail cam 42. When shaft 2 has been rotated a slight fraction in advance of zero position upon the completion of the re-setting operation, pin 47 comes into engagement with notch 46 on stop lever 45 and, further progressive rotation of shaft 2 is prevented. The slight fractional movement beyond zero position permits cam lever 44 to drop into the mutilated portion of the cam under the influence of spring 48, in which position it prevents rearward movement of shaft 2. When setting wheel 49, by means of which shaft 2 is turned, is then released, the pressure of cam lever 44 against the mutilated edge of snail cam 42 reversely rotates shaft 2 the slight fraction to which it has been advanced beyond zero position, and when exact zero position is reached, stop lever 45 is released from pin 47 and under the influence of spring 32, all of the carrying mechanism which has been held out of engagement with the accumulating mechanism is swung back into engagement therewith. Hand wheel 49 is provided about its periphery with the notches 49^a which are engaged by a spring pressed pawl 51 to prevent reverse rotation of shaft 2 during the re-setting operation. As soon as pawl 51 engages the serrated portion of wheel 49 the reverse rotation of shaft 2 is precluded until wheel 49 has been completely rotated to return all accumulating mechanism to zero. A portion 49^b of the periphery of the hand wheel is left without serrations so that the hand wheel may escape reversely during the fractional reverse movement of the shaft between the time

when cam lever 44 drops into engagement with the mutilated portion of the cam, and stop lever 45 is released from engagement with pin 47.

5 It will be obvious by virtue of the arrangement above described that I have produced a register wherein a digit will be carried from units to tens order upon alternate operations of the units accumulating mechanism, and a carrying mechanism for carrying between units and tens and tens and hundreds which is operated by carrying pawls actuated from the operating mechanism of the cash register. These features 10 are claimed in my application No. 704,995.

In addition to the foregoing, it will be obvious that I have provided a means whereby all the carrying mechanism may be rocked out of engagement with the accumulating mechanism and held out of engagement therewith during the resetting operation, mechanism whereby the parts may be positively retained in proper position for reengagement while thus disengaged, and 20 means for insuring the accumulating mechanism being in exact zero position when the carrying mechanism is reengaged therewith.

I am aware that modifications may be 30 made in the construction illustrated without departing from the scope of my invention, and I therefore do not intend that my invention be limited in scope to the particular form illustrated and described.

35 What I claim is:

1. In a register, a 5¢ register plate, a 10¢ accumulating wheel, means for reversely oscillating the plate on alternate operations thereof, means for retaining said plate in its extreme positions, means for carrying into 40 said tens wheel on alternate operations of

said plate, and a re-setting mechanism for said register including means adapted to return said plate to zero position.

2. In a register, the combination of a re-setting shaft, a 5¢ register plate, a rocking frame, means operable by said re-setting shaft for rocking said rocking frame during the re-setting operation, and means operable by said rocking frame for returning 50 said 5¢ register plate to zero position.

3. In a register in combination, an accumulator wheel, a register plate, actuating means for oscillating said register plate, carrying mechanism coöperating with said 55 accumulator wheel, the operation thereof being controlled by said actuating means, a re-setting mechanism including means for preventing coöperation of the carrying mechanism with the accumulator wheel, said re-setting mechanism including means for returning said register plate to zero position.

4. In a register, the combination of an accumulator wheel, an oscillating register plate, a re-setting mechanism for returning 60 65 said accumulator wheel to zero, and means operable from said re-setting mechanism for returning said register plate to zero position.

5. In a register in combination, an accumulator wheel, an oscillating register plate, actuating means for the latter, and a re-setting mechanism adapted to oscillate said 70 75 register plate in its reverse direction.

In testimony whereof I hereunto affix my signature in the presence of two witnesses, this 1st day of May, 1913.

ELMER E. PATTEN.
